APPARATUS FOR TRANSMITTING ENERGY

Irving C. Harris, Los Angeles, and Harry W. Doubrava, Beverly Hills, Calif.

Application March 25, 1932, Serial No. 601,156

16 Claims. (Cl. 103—45)

This invention relates to methods of transmitting energy through passageways of small diameter from a source at one elevation to a lower elevation for the purpose of actuating energy using devices at the lower elevation, as for example, devices used in connection with the drilling and operation of wells, drainage of mines, and for other purposes.

Wells drilled for petroleum and gas are of relatively small diameter; and a great percentage of them are very deep. They penetrate both unconsolidated and consolidated formations of great hardness and resistance to drilling operations; and the transmission of the necessary energy from the source above ground to the bottom for the operation of the cutting tools presents a difficult problem, especially in the drilling of the deeper wells.

The completed wells range in depth up to eight thousand feet and have strings of casing ranging from $8\frac{3}{8}$ " down to $4\frac{3}{4}$ " in diameter. After the virgin gas pressure has been depleted and the oil must be lifted by external means from depths of from one to several thousand feet, energy must be transmitted these distances through these small bores for the lifting of the oil to the ground surface.

Various methods have been used for transmitting the energy for the purposes named with a measure of success, but attended by serious difficulties which leave much room for improvement. In drilling wells, two methods of transmitting the energy to the bottom are in common use. With the churn-drill, or cable tool drill, the cutting bit is lifted and dropped repeatedly by means of a cable; and the energy is transmitted through the cable by the intermittent pulling of the cable by means at the surface of the ground. With the rotary drill, the cutting bit is rotated about the axis of the bore under heavy rotative torque and under heavy downward pressure on the bit; and the energy is transmitted through the long, slender drill-stem from above ground to the bit as a torque which ranges up to a maximum that frequently twists the drill-stem in two.

The cable tool method has certain advantages and certain disadvantages which limit its use to certain fields. The rotary method has superseded the cable tool to a very large extent due to certain advantages; but the method of transmitting the energy to the cutting tools as a rotative torque, transmitted through a long slender drill stem, is one of the causes of the drilling of very crooked holes and many other

troubles which render it very desirable to find a better method.

In pumping from deep wells, the so called "sucker-rod pump" has been very largely used. It transmits its energy to the bottom as a series of pulls through a long line of rods; and there are many serious difficulties with this method, especially in the deeper wells. Air-lift, gas-lift, and displacement gas-lift methods have been used quite satisfactorily in certain ranges of operation; but they all have limits as to the maximum depth from which they will pump oil satisfactorily; and there is need for pumping oil from depths beyond these limits.

Various methods have been considered for overcoming these difficulties, including electric, hydraulic, pneumatic, and mechanical means of transmission of the energy. There are certain inherent obstacles that prevent these from being entirely satisfactory. Any method to be completely satisfactory must fulfill the following requirements:

1st.—It must transmit the energy from above ground to the drilling, pumping, or other device in the well without torque or twisting action on the pipe or other member connecting the device at the bottom with the apparatus above ground.

2nd.—It must transmit the energy from above ground to the device at the bottom without subjecting the pipe or other connecting means to reversals or large variations in stress, either in the form of rotative torque, axial tension or compression, or hydraulic pressure within or without the pipe.

3rd.—It must transmit the energy from above ground to the device at the bottom without subjecting a long column, or long columns of fluid, to repeated, sudden, or severe changes in flow or pressure.

The present invention provides a method of transmitting energy which, for example, may be used for transmitting energy from above ground to the bottom of a well or shaft of any depth for the operation of any energy using device at the bottom; and it accomplishes the result by means which meet all of the requirements stated above. We attain the stated objective by the means described in the following specification and illustrated by the accompanying drawing of a specific embodiment of the invention, in which, Fig. 1 is an axial section of the apparatus installed in a well and adapted to pumping liquid from the well, Fig. 2 a view showing details of

a nozzle sleeve, and Fig. 3 shows details of the motor valve.

The apparatus installed in the well consists of two concentric strings of tubing, parts 13 and 14 of Fig. 1, connecting the various units with each other and with the apparatus above ground, and providing a conduit for the circulation of a flow of fluid downward to the bottom of the apparatus from above ground in the inside of the inner string of tubing 14, as indicated by the arrows, and upward to the starting point in the space between the two strings of tubing, as indicated by the arrows. Throughout parts of the length of the apparatus, other strings of tubing of small bore, designated gas-lines, parts 12 and 21, are installed within the inner tubing 14, making three concentric strings for part of the length and two for the rest.

At the lower end of the apparatus, is an assembly of parts constituting a separator and a pump, of which parts 1 are pump inlet valves, parts 2 pump discharge valves, part 3 the pump cylinder, part 4 the power cylinder, 5, 6, 8, 9, 40, and 41 passageways, part 7 a valve controlling the power cylinder, 10 the nozzle sleeve, 11 the separator chamber, and 8 the outlet from the separator chamber.

Situated at a point above the separator is a mixer chamber 15 supported by a spider 16, the mixer chamber being a cylinder, open at the bottom, closed at the top, and connected to the separator at the bottom by means of gas-line 12 in such a way that gas ascending in 12 will enter mixer chamber 15 near the top. The descending flow of fluid can pass the mixer chamber, and gas entering the chamber may pass out at the bottom and join the descending flow of fluid.

At a point above the mixer is a second separator, which may be the same as the lower one or of an inverted form, as shown, of which, 20 is the separator chamber, formed by inner sleeve 18 and outer sleeve 19. The ascending flow of fluid passes through nozzles 17. The descending flow of fluid passes the separator through openings in the supporting spider.

At a point near the upper end of the apparatus in the well is a second mixer of the same construction as the lower one but differently connected as to the gas-line. The mixer chamber is indicated at 23; and the descending flow of fluid passes it through passageways 22. The gas-line 21 leads from the second, or upper, separator through the upper mixer without connecting to it and conveys gas to outlet 24. Gas may be conveyed into the upper mixer through the inlet 25 and the connecting passageways, as indicated by arrows.

Above ground is a tank 27, and some form of a pump, indicated at 26, is connected with the apparatus in the well and tank 27 by passageways 29 and 30 in a manner such that the pump 26 may be used to pump fluid from the tank 27 through the circuit of conduits in the well, as described, and back to the tank again.

The method of operation is described as follows: With an initial charge of the liquid to be pumped in tank 27 sufficient to fill the system, the pump 26 is operated to establish and continuously maintain a circulation of the liquid to the separator chamber 11 through the inner tubing 14 and back to the point of beginning through the space between the inner tubing 14 and the outer tubing 13, and through the passageways through the two separators and the

two mixers as indicated by the arrows on the drawing and hereinbefore described. An initial charge of gas from the well, an adjacent well, or from any other source, admitted through inlet 36, is compressed by compressor 35 and introduced through inlet 25 to the circulation in the well, into mixer chamber 23 where it passes downward into the flow of liquid moving downward in the inner tubing. The velocity of flow of the liquid is maintained far above the rate of rise of gas in the liquid due to its buoyancy; and the gas is carried downward with the liquid to the separator chamber 11 at the bottom; and the gas is compressed by the liquid in descending from the pressure at mixer chamber 23 to the pressure at the separator chamber 11, the amount of compression being proportional to the weight of the column of liquid and gas between the two points.

The mixture of liquid and gas enters the separator chamber 11 through nozzles 10, which are spiral passageways, as indicated in Fig. 2, which cause the mixture to whirl and form a vortex within the chamber. The liquid weighs from 50 to 62 pounds per cubic foot and the gas weighs from .08 pounds to 10 pounds per cubic foot, approximately,—the lower value being at about atmospheric pressure and the higher at about 2000 pounds per square inch. Owing to this large difference in weight of the liquid and the gas and the fact that the mixture is forced by the pressure of the circulating pump 26 and the shape, dimensions, and angularity of the nozzles 10, to enter chamber 11 and move in a spiral of small diameter and at high velocity,—thereby causing a large centrifugal effect,—the liquid, due to its greater weight, is forced to move spirally downward in a thin sheet against the outer cylindrical wall of separator chamber 11, and the gas, due to its lighter weight, is forced to form a core of gas, in the center of chamber 11, inside of the liquid.

Gas may be withdrawn at the upper end of chamber 11, near the center, through passageway 9, provided the rate of withdrawal is not greater than that of the gas entering through nozzles 10. Gas in excess of the amount passing out through passageway 9, passes out through outlet 8 with the liquid. Withdrawal of gas through outlet 9 requires a slight drop in pressure beyond outlet 9 to cause flow from separator chamber 11 to the cylinder 4, through valve 7. The drop in pressure and the amount of gas withdrawn is regulated by the conditions in the motor to an amount less than the total amount of gas circulated and entering chamber 11 through nozzles 10. As long as there is an excess of gas beyond the withdrawal through outlet 9, the excess gas must pass out with the liquid through outlet 8. Liquid can not pass out through outlet 9 as long as there is sufficient gas to keep the upper end of the chamber 11, above the level of the nozzles 10, filled with gas.

The gas which passes out through outlet 8 with the liquid, passes upward to the second separator chamber 20 where the same action takes place as described for separator chamber 11, except that the second separator is an inverted form which functions in a similar manner. The liquid passes upward in the conduit between the inner tubing and the outer tubing,—tubing 13 and 14,—to the tank 27; and the gas passes upward through gas-line 21 to outlet 24. Outlet 24 may be connected to outlet 25 direct and the gas re-circulated; but, generally, the gas

is taken from outlet 24 to a treatment plant. The treatment plant for treating the gas, indicated by parts 33, 34, 35, and 36 on the drawing, may be of any type or may consist of any equivalent that will insure the delivery through inlet 25 of the quality, quantity, and pressure of gas required for the operation of the apparatus.

The circulations of liquid and gas and mixture of liquid and gas are forced to take the various paths, as indicated by the arrows on the drawing and as described herein, for the reason that the pressure gradients throughout the circuits are such as to produce these circulations. The forces producing the separations have been described. The separator 11 and the mixer 15 are at widely different elevations which may be of the order of many hundreds of feet, even thousands of feet. The weight of the gas per square inch of cross section, in the gas-line 12 between the separator 11 and the mixer 15, is a very small fraction of the weight of the fluid, per square inch of cross section, in the space between tubing 14 and tubing 12, between the two elevations. The friction loss in the gas-line 12 is, also, less than the friction loss in the space between tubing 14 and tubing 12, owing to the difference in the friction losses of liquids and gases. Due to these differences, there is a difference of pressure between the outlet 9 of the separator and the gas inlet of the mixer 15, as long as gas alone is allowed to pass through gas-line 12; and the pressure difference may range up to 1000 pounds per square inch in deep installations. This difference in pressure and the quantity of gas withdrawn from the separator through outlet 9 and returned to the circulation through the mixer 15, are measures of the energy used in the energy using device, the pumping apparatus represented by the motor cylinder 4 in this embodiment of the invention. This energy, withdrawn from the circulation circuit at this point and consumed, is put into the circulation circuit by the pumping means at the upper end of the apparatus and is transmitted through the circulation circuit as described.

It has been stated how the outflow of gas from separator 11 through outlet 9 is controlled. The return of the gas entering the mixer through gas-line 12 to the descending flow of mixture is forced by definite and positive causes. The gas must pass out of the mixer as fast as it comes in; because any tendency to reduce the flow of gas out of the mixer is met by a rise in pressure, due to the decrease in pressure drop in conduit 12,—caused by the decreased flow,—which rise in pressure overcomes the tendency to reduce the flow. The pressure in the mixer chamber must be the same as the pressure at that elevation in the conduit carrying the descending flow of fluid with which it communicates, and cannot rise above that pressure. Liquid cannot enter the mixer chamber and pass out into gas-line 12 as long as the upward flow of gas in gas-line 12 and into the mixer is maintained. The action that takes place between the second separator 20 and the second mixer 23 is very much the same, except that the difference in pressure between the two is only just enough for the regulation of the flow.

No liquid can go out through the gas outlets of the separators as long as there is more gas coming into the separators with the mixture than is going through the gas outlets; and the excess gas goes out of the separators with the

liquid. It is merely necessary to maintain in the circulating system gas in excess of that required to pass through the energy using device and gas-line 12, and to regulate the flow of gas between outlet 24 and inlet 25.

The gas separated out by separator chamber 11 is conveyed through passageway 8 to valve 7, which controls its admission to and discharge from motor cylinder 4. Valve 7 may be of any type and actuated in any manner, such as by 10 means of a valve-rod 31, which is actuated by engagement with shoulders 32 and 33 of the piston in motor cylinder 4, as the piston approaches the respective ends of the piston's stroke. The motor piston is reciprocated by the 15 alternate admission and discharge of gas through the passages 40 and 41, which are opened and closed in sequence by valve 7, after the manner of an ordinary double acting steam pump. The gas enters the motor cylinder from 20 separator 11, through port 9, valve 7, and passage 40 (or 41) at the pressure of the separator chamber 11, less a slight friction drop; and, upon completion of the half stroke, is vented through passage 40 (or 41) valve 7, and gas-line 12, to mixer 15, and expands to the lower pressure of mixer 15,—less a small friction drop. The return half of the stroke is made with the opposite side of the piston being acted upon by the higher pressure from the separator 11 and 30 the first stated side by the lower pressure of the mixer 15, plus a slight difference due to the weight of the column of gas under pressure between the two points.

The desired pressure difference across the piston in motor cylinder 4 is controlled by the distance between the mixer 15 and the separator 11 and the amount and relative quantities of liquid and gas circulated between the two points. The descending column of mixture and the ascending column of gas must be in dynamic pressure balance between the two elevations, allowing for all factors. In the descending column, there is the unit weight of the liquid, the unit weight of the gas,—allowing for the progressive increase 45 in weight with pressure,—and the friction loss. In the ascending column, there is the unit weight of the gas,—allowing for the progressive change in weight with pressure,—the friction loss, and the pressure difference utilized by the 50 motor. The aggregate of these factors in the ascending column must balance the descending column. This balance is produced and maintained by proper proportioning of the component parts in installation and by manual or automatic regulation of the circulating pump, compressor, and other apparatus at the upper end of the apparatus, the means of accomplishing this regulation not being parts of the present 55 invention.

In the specific embodiment of the invention shown, the gas used through the motor is returned to the descending column of the circulating circuit. It is not necessary to return it at this point. It may be returned at other 65 points in the circulation having a similar relationship as to pressure as compared with the pressure at the lower separator. For example, the gas may be returned from the motor to the ascending column at a point having a suitable 70 pressure; or, it may be returned at the upper mixer, dispensing with the lower mixer. In these cases, the gas has farther to travel in making the circuit, the distribution of the gas is different in the descending column, and the 75

5 performance is modified; but the same laws govern. The elevation of the second, or upper, separator may be varied. It may be placed at the upper end of the apparatus; in which case, 10 the gas separated out by it goes to the treatment plant at a lower pressure than is the case when located as previously described; and this difference in pressure is made up by the compressor 34 before the gas is returned to the circulation at mixer 23. Tank 27 may be open as shown, or closed; and the tank 27 and the separator 28 may be operated at atmospheric pressure or with a back-pressure above atmospheric, 15 all without departure from the basic principles of this invention.

10 Gas in excess of that needed by the local circuit through pump power cylinder 4 is automatically rejected at 8 by separator 11 and passes upward to separator 28, where it is separated from the liquid and conveyed through passageway 21 to outlet 24. Separator 28 is located at a distance below ground such that the pressure of the gas separated out and conveyed to outlet 24 is slightly higher than the pressure produced by circulating pump 26 at the point where gas from mixer 23 enters the descending flow of liquid at 22. This makes it possible for the gas issuing at outlet 24 to be put back into the circulation through inlet 25 and mixer 23 without re-compressing; thus saving the use of a mechanical compressor at the ground surface.

20 When pumping petroleum, a certain amount of gas comes into the circuit with the oil and insures an abundance of gas, if there are no large losses, after the initial charge is introduced. It is found that gas, thus circulated, accumulates gasoline vapor and that it can be put through apparatus for extracting the gasoline indicated at 38; after which, the gas is returned to the circulation again. This operation can be readily provided for between outlet 24 and inlet 25.

25 Having described the manner of reciprocating the power piston of the pump at the bottom, it is easy to be seen that the pump cylinder 3 will draw oil from the space in the well external to the apparatus through inlet valves 1 and discharge it through discharge valves 2 and passageway 6 into the circulating system at 8, from 30 which point, the pumped oil is carried upward with the circulating oil to tank 27; and the excess of oil resulting is withdrawn at outlet 28.

35 It is to be seen that the same system of transmitting energy can be used to operate any other kind of apparatus at the bottom of a well, and that it may be used in places other than in a well. In the specific embodiment used to illustrate the invention, the fluid pumped by the energy using device is injected into the circulation circuit for the primary purpose of conveying it to the ground level without the necessity of providing a separate conduit; but this is not an essential part of the present invention.

40 Having described the invention it is pointed out that it fulfills all of the stated objects, in that it provides means of transmitting energy from above ground level to any depth in a well without submitting any part of the connecting structure to rotative torque, without subjecting the connecting pipes or strings of tubing to reversals or large variations in stress either in the form of rotative torque, axial tension or compression, or hydraulic pressure, and without subjecting a column, or columns, of fluid to repeated, sudden, or severe changes in flow or

5 pressure. The circulation is maintained as a steady flow with little change or variation. The virgin oil is injected into the circulation, when the device is used to actuate a pump; but the amount injected per stroke is very small in proportion to the amount of fluid in the circulation and would cause but little change in the circulation in any case; but, when the liquid is being injected into the circulation, a somewhat larger volume of gas is being withdrawn from an adjacent point in the circulation at the same half-stroke; and the same amount of gas, expanded to larger volume, withdrawn at the preceding half-stroke, is returned to the circulation at a lower pressure and hundreds of feet higher up 10 the ascending column of fluid at the said same half-stroke. The net effect on the circulation is very small and not disturbing in the least. The pump is reciprocated by gas, an expansible fluid which gives a cushioning effect; and there are 15 no severe shocks such as accompany the use of liquid alone for such purposes.

20 Attention is called to the fact that the use of a mixture of liquid and gas in circulation, as described, performs important functions. It 25 provides an hydro-pneumatic compressor which automatically supplies the variable gas pressures required in operating the apparatus with the energy using device at distances below the upper end which may vary widely during the operating life of a single installation, requiring 30 gas pressures that may range from 300 to 3000 pounds per square inch. To accomplish this result with mechanical compressors would require a very costly installation of several compressors; whereas, with the apparatus described, 35 the high pressure and the variable pressure requirements are met by a very simple and comparatively inexpensive liquid pump, pump 26, with a maximum pressure capacity of not over 40 800 pounds per square inch. The hydro-pneumatic compressor is very efficient, is practically isothermal in operation, and involves no cooling problems. With a mechanical compressor installation, cooling of the compressor and the gas 45 would be required. The variations in the depth at which the energy using device operates and the consequent gas pressures required are met by changes in the elevations of the said device and the separators and mixers. The changes 50 in the pressures required to be delivered by pump 26 are small compared with the changes in the pressure at the said device.

55 Attention is called to the fact that the method is very flexible and capable of a large variation in method of operation to suit the specific purposes to be accomplished or the characteristics of the available facilities to be used in combination with the method. The pumping means at the ground surface may be operated to maintain a constant rate of flow of liquid, the pressure varying as necessary, or at a constant pressure with the flow varying as necessary. Each 60 method has its own performance characteristics which suit certain conditions to be encountered 65 in certain fields.

65 We have illustrated and described a preferred form of the invention; but we call attention to the fact that it is capable of a wide range of variations without departing from the basic 70 principles of the invention. Various combinations of parts are possible. It may be operated with all of the component parts described in use, or with some of them omitted or modified. It may be operated with a second mixer and a 75

second separator, or with either or both omitted or located in a different position in the circuit. Different combinations of the conduits for the circulation of the liquid and the conveyance of the gas are possible. We do not limit ourselves to the exact details of construction disclosed but may employ such changes in construction and arrangement of parts, and such modifications and equivalents as come within the scope of the appended claims.

10 We claim:

1. In apparatus of the character described, pumping means at the upper end of the apparatus, strings of tubing, connected to the pumping means and connected together at their lower ends in a manner to form a circuit through which a circulation of fluid may be maintained by the pumping means; a separator, near the lower end of the strings of tubing, adapted to 15 separate gas from liquid; an energy using device adapted to receive gas from the separator; a mixer adapted to receive gas from the said device and return it to the circulation of fluid; means of conveying gas from the said device to 20 the mixer; and means of introducing gas into the circulation of fluid.

2. In apparatus of the character described, pumping means at the upper end of the apparatus, strings of tubing, connected to the pumping means and connected together at their lower ends in a manner to form a circuit through which a circulation of fluid may be maintained by the pumping means; a separator, near the lower end of the strings of tubing, comprising 25 a chamber, an outlet for fluid connected to the conduit conveying the flow of fluid ascending toward the pumping means, an outlet for gas near the axis of the chamber, and inlet passages connected to the conduit conveying the flow of fluid descending from the pumping means, the inlet passages being so formed and disposed as to cause the entering fluid to enter and proceed in a generally spiral direction along the outer wall of the chamber; an energy using 30 device adapted to receive gas from the separator; a mixer adapted to receive gas from the said device and return it to the circulation of fluid; means of conveying gas from the said device to the mixer; and means of introducing gas into the circulation of fluid.

3. In apparatus of the character described, pumping means at the upper end of the apparatus, strings of tubing, connected to the pumping means and connected together at their lower ends in a manner to form a circuit through which a circulation of fluid may be maintained by the pumping means; a separator, near the lower end of the strings of tubing, comprising 35 a chamber, an outlet for fluid connected to the conduit conveying the flow of fluid ascending toward the pumping means, an outlet for gas near the upper end of the chamber, and inlet passages connected to the conduit conveying the flow of fluid descending from the pumping means, the inlet passages being so formed and disposed as to cause the entering fluid to enter and proceed in a generally spiral direction along the outer wall of the chamber, the direction of 40 rotation of the spirally moving fluid being counter-clockwise when viewed from above; an energy using device adapted to receive gas from the separator; a mixer adapted to receive gas from the said device and return it to the circulation of fluid; means of conveying gas from the 45

said device to the mixer; and means of introducing gas into the circulation of fluid.

4. In apparatus of the character described, pumping means at the upper end of the apparatus, strings of tubing, connected to the pumping means and connected together at their lower ends in a manner to form a circuit through which a circulation of fluid may be maintained by the pumping means; a separator, near the lower end of the strings of tubing, comprising a 50 chamber, an outlet for fluid, connected to the conduit conveying the flow of fluid ascending toward the pumping means, and outlet for gas near the upper end of the chamber, and inlet passages connected to the conduit conveying the flow of fluid descending from the pumping means, the inlet passages being so formed and disposed as to cause the entering fluid to enter and proceed in a generally spiral direction along the outer wall of the chamber, the direction of 55 rotation of the spirally moving fluid being clockwise when viewed from above; an energy using device adapted to receive gas from the separator; a mixer adapted to receive gas from the said device and return it to the circulation of fluid; means of conveying gas from the said device to the mixer; and means of introducing gas into the circulation of fluid.

5. In apparatus of the character described, pumping means at the upper end of the apparatus, strings of tubing, connected to the pumping means and connected together at their lower ends in a manner to form a circuit through which a circulation of fluid may be maintained by the pumping means; a separator, near the lower end of the strings of tubing, adapted to 60 separate gas from liquid; a mixer situated at a distance above the separator and comprising a chamber with a gas inlet and a connection with a conduit of the circuit which conveys the flow of fluid circulated by the pumping means; an energy using device connected to receive gas from the separator and discharge the same into the inlet of the mixer; and means of introducing gas into the circulation of fluid.

6. In apparatus of the character described, pumping means at the upper end of the apparatus, two strings of tubing, connected to the pumping means and connected together at their lower ends in a manner to form a circuit through which a circulation of fluid may be maintained by the pumping means, the connecting means comprising a separator, consisting of a chamber, an outlet for fluid connected to the conduit conveying the flow of fluid ascending toward the pumping means, a gas outlet near the upper end of the axis of the chamber, and inlet passages connected to the conduit conveying the flow of fluid descending from the pumping means, the inlet passages being so constructed and disposed as to cause the entering fluid to whirl spirally along the outer wall of the chamber; a mixer situated at a distance above the separator and comprising a chamber having a gas inlet and a connection with a conduit conveying the flow of fluid circulated by the pumping means; an energy using device adapted to receive gas from the gas outlet of the separator; a conduit connecting the energy using device with the gas inlet of the mixer and adapted to convey to the mixer gas exhausted by the said device; and means of introducing gas into the circulation of fluid.

7. In apparatus of the character described, pumping means at the upper end of the appa-

tus, an assembly of tubing, connected to the pumping means and connected together at the lower end in a manner to provide a circuit of conduit through which a circulation of fluid 5 may be maintained by the pumping means; an energy using device attached at the lower end of the assembly of tubing; a separator adjacent to the said device and connected to it and to the circuit of conduit and adapted to separate 10 gas from the circulating fluid and deliver it to the said device; a mixer situated at a distance above the separator and connected and adapted to receive gas from the said device and deliver it into the conduit conveying the flow of fluid 15 descending from the pumping means; a second separator situated above the mixer aforesaid and connected into the conduit conveying the flow of fluid ascending toward the pumping means; a second mixer situated at a distance above the 20 second separator and connected into the conduit conveying the flow of fluid descending from the pumping means; means of introducing gas into the circulation of fluid; and a conduit connecting the gas outlet of the second separator with 25 the gas inlet of the second mixer.

8. In apparatus of the character described, pumping means at the upper end of the apparatus, an assembly of tubing, connected to the pumping means and connected together at the 30 lower end in a manner to provide a circuit of conduit through which a circulation of fluid may be maintained by the pumping means; an energy using device attached at the lower end of the assembly of tubing; a separator adjacent to the said device and connected to it and to the circuit of conduit and adapted to separate 35 gas from the circulating fluid and deliver it to the said device; a mixer situated at a distance above the separator and connected and adapted 40 to receive gas from the said device and deliver it into the conduit conveying the flow of fluid descending from the pumping means; a second separator situated above the mixer aforesaid and a second mixer situated at a distance above 45 the second separator, the second separator being adapted to separate gas from the fluid ascending from the lower separator to the pumping means, and the second mixer being adapted to deliver gas into the flow of fluid descending 50 from the pumping means; a line of conduit connected to convey gas from the gas outlet of the second separator to the ground surface, thence to a plant for treating the gas, thence to the gas 55 inlet of the second mixer.

55 9. In apparatus of the character described, pumping means near the ground level; strings of tubing, installed in a well, connected to the pumping means and connected together at their lower ends in a manner to form a circuit through 60 which a circulation of fluid may be maintained by the pumping means; a separator, near the lower end of the strings of tubing, adapted to separate gas from liquid; an energy using device adapted to receive gas from the separator; a mixer adapted to receive gas from the said device and return it to the circulation of fluid; a second separator situated above the mixer and adapted to separate gas from the flow of 65 fluid ascending from the first named separator; a line of conduit connected to convey gas from the gas outlet of the second separator to a plant for treating the gas; means of introducing gas 70 into the circulation of fluid.

75 10. In apparatus of the character described,

pumping means near the ground level; strings of tubing, installed in a well, connected to the pumping means and connected together at their lower ends in a manner to form a circuit through which a circulation of fluid may be 5 maintained by the pumping means; a separator, near the lower end of the strings of tubing, adapted to separate gas from liquid; an energy using device connected to receive gas from the separator and discharge the same into the inlet 10 of the mixer; a mixer situated at a distance above the separator and adapted to receive gas from the said device and return it to the flow of fluid descending from the pumping means; an upper mixer situated near the upper end of 15 the apparatus and comprising a chamber with a bottom outlet connected to the conduit conveying the flow of fluid descending from pumping means and a gas inlet at the upper end connected to a source from which compressed gas 20 may be supplied.

11. In apparatus of the character described, pumping means at the upper end of the apparatus; strings of tubing connected to the pumping means and connected together at their lower ends in a manner to form a circuit through which a circulation of fluid may be maintained by the pumping means; a separator, near the lower end of the strings of tubing, adapted to separate gas from liquid; an energy using device adapted to receive gas from the separator; a mixer adapted to receive gas from the said device and return it to the circulation of fluid; means of conveying gas from the said device to the mixer; means of introducing into and maintaining in the circulation the required amount of liquid; means of introducing into and maintaining in the circulation the required amount of gas.

30 12. In apparatus of the character described, 40 pumping means at the upper end of the apparatus; strings of tubing connected to the pumping means and connected together at their lower ends in a manner to form a circuit through which a circulation of fluid may be maintained 45 by the pumping means; a separator, near the lower ends of the strings of tubing, comprising a chamber, an outlet for fluid connected to the conduit conveying the flow of fluid ascending toward the pumping means, an outlet for gas 50 near the upper end of the chamber, and inlet passages connected to the conduit conveying the flow of fluid descending from the pumping means; an energy using device adapted to receive gas from the gas outlet of the separator; a mixer connected and adapted to receive gas from the said device and return the gas to the circulation of fluid at a point having a pressure lower than the pressure at the gas 55 outlet of the separator; means of maintaining liquid and gas within the circulation system in the required quantity.

65 13. In apparatus of the character described, pumping means at the upper end of the apparatus; strings of tubing connected to the pumping means and connected together at their lower ends in a manner to form a circuit through which a circulation of fluid may be maintained by the pumping means; a separator, near the lower end of the strings of tubing, adapted to 70 separate gas from liquid; an energy using device adapted to receive gas from the separator; a mixer connected and adapted to receive gas from the said device and return it to a point in the conduit carrying the flow of fluid ascend- 75

ing from the separator, the said point having a pressure lower than the pressure of the gas delivered from the separator to the said device; means of maintaining liquid and gas within the circulation system in the required amount.

14. In apparatus of the character described, pumping means at the upper end of the apparatus; strings of tubing connected to the pumping means and connected together at their lower ends in a manner to form a circuit through which a circulation of fluid may be maintained by the pumping means; a separator, near the lower end of the strings of tubing, adapted to separate gas from liquid; an energy using device adapted to receive gas from the separator; a mixer connected and adapted to receive gas from the said device and return it to a point in the conduit carrying the flow of fluid descending to the separator, the said point having a pressure lower than the pressure of the gas delivered from the separator to the said device; means of maintaining liquid and gas within the circulation system in the required amount.

15. In apparatus of the character described, pumping means at the upper end of the apparatus; strings of tubing connected to the pumping means and connected together at their lower ends in a manner to form a circuit through which a circulation of fluid may be maintained by the pumping means; a separator, near the lower end of the strings of tubing, adapted to separate gas from liquid; an energy using device adapted to receive gas from the separator; a mixer connected and adapted to receive gas from the said device and return it to a point in the circulation of fluid having a pressure lower than the pressure of the gas received by

the said device from the separator; a second separator near the upper end of the apparatus and connected and adapted to separate gas from the fluid in the circulation ascending to it from below; a second mixer near the upper end of the apparatus and adapted to inject gas into the circulation circuit; means of conveying gas from the second separator to the second mixer; means of maintaining liquid and gas within the circulation system.

16. In apparatus of the character described, pumping means at the upper end of the apparatus; strings of tubing connected to the pumping means and connected together at their lower ends in a manner to form a circuit through which a circulation of fluid may be maintained by the pumping means; a separator, near the lower end of the apparatus, adapted to separate gas from the fluid in the circulation; an energy using device adapted to use gas from the separator to actuate the said device; a mixer connected and adapted to receive gas from the said device and return it to the circulation at a point having a pressure lower than the pressure of the gas received by the device from the separator; a second separator near the upper end of the apparatus and connected and adapted to separate gas from the fluid in the circulation ascending to it from below; a second mixer near the upper end of the apparatus and adapted to inject gas into the circulation circuit; means of conveying gas from the second separator to a plant for treating the gas and returning it to and injecting it into the mixer; means of supplying liquid and gas to the circulation system.
